UNITED STATES PATENT OFFICE.

GEORGE E. MOLYNEUX, OF BAYONNE, NEW JERSEY.

SPEED-GOVERNED STOPPING MECHANISM.

1,285,312.

Specification of Letters Patent. Patented Nov. 19, 1918.

Application filed September 22, 1915. Serial No. 51,930.

To all whom it may concern:

Be it known that I, GEORGE E. MOLYNEUX, a citizen of the United States, and residing in the city of Bayonne, county of Hudson, 5 in the State of New Jersey, have invented certain new and useful Improvements in Speed-Governed Stopping Mechanisms, of which the following is a specification, reference being had to the accompanying drawings, forming a part hereof.

In another application, filed August 31st, 1915, Serial Number 48,191, there is shown and described an improved mechanism for arresting quickly the motion of high speed 15 machines without shock or jar or undue wear, such mechanism having been designed with a view to overcoming difficulties incident to the use of other mechanisms intended for the same general purpose and to the 20 production of a comparatively simple and compact mechanism complete in itself and capable of application readily to sewing machines in use, without reconstruction, and avoiding the use of a dog carried by a movable 25 rotatable part and acted upon directly by centrifugal force, and also avoiding the use of coöperating stop-members movable relatively toward and from each other in an axial direction and requiring the use of 30 locking means for locking them against such relative movement. The present invention is embodied in a mechanism which is similar in some respects to the mechanism shown and described in the said application; it 35 avoids the use of a movable dog carried by a rotating part, and while it has a stop-member movable in an axial direction with respect to another stop-member, it has no positive locking means to lock such member 40 positively against movement.

The improved mechanism comprises a relatively fixed stop-member, a rotating stop-member pressed normally toward the fixed member, a centrifugal body mounted 45 for radial movement in a rotating member and at high speeds closing a gap therein and forming a continuous track, and a detector finger carried by a relatively fixed member and bearing at high speeds upon 50 the continuous track completed by the centrifugal body and adapted to be received in such gap when the speed falls below the predetermined minimum so as to permit the rotating member to move into engagement 55 with the fixed member. The invention will be more fully explained hereinafter with

reference to the accompanying drawings in which it is illustrated and in which—

Figure 1 is a view in elevation of the improved mechanism, with a portion of the 60 bed-plate and arm of a sewing machine shown in section.

Fig. 2 is a similar view but with all of the parts except the central shaft and a portion of the controlling arm in longitudinal section.

Fig. 3 is a view in elevation as seen from the left hand in Figs. 1 and 2, with the central shaft in section and a portion of the rotating member broken away to show 70 the relatively fixed member beyond it.

Fig. 4 is a detail view in perspective of the centrifugal body carried by the rotating member.

Fig. 5 is a detail view in perspective of 75 the annulus which forms a part of the rotating member.

Fig. 6 is a similar view of the relatively fixed member.

Fig. 7 is a similar view, partly broken 80 away, of the inner portion or body of the rotating member.

The mechanism is shown as applied to an ordinary sewing machine, the bed-plate of which is indicated at *a*, the usual arm at *b* 85 and the driving shaft at *c* with its driving pulley *d*.

The relatively fixed member *e* of the mechanism, carrying the stop-lug *e'* on its left hand face, is shown as secured to the 90 inner or left hand face of the vertical arm *b* in such manner as to have a limited movement for the purpose of cushioning the shock when the mechanism operates, loosely encircling the shaft *c*. It is secured to the 95 face of the arm *b* by screw-bolts *f* provided with washers *f'* and passing through arc-shaped slots *e*² in the stop-member *e* into the face of the arm *b*, a limited movement of the member *e* being thus permitted. The 100 member *e* is also provided with a lug *e*³ which is cushioned by a heavy spring *g* and a lighter spring *g'* which are seated on abutments *g*² and *g*³ on the inner face of the arm *b*, the spring *g* cushioning the movement 105 of the member *e* in stopping and the spring *g'* cushioning the rebound. The member *e* is also provided with a detector finger *e*⁴ parallel with the axis of the member *e*.

Mounted on the shaft *c* is the rotatable 110 stop-member *h* held by a key *h'* so as to rotate with the shaft but arranged to be moved

longitudinally thereon. For convenience in manufacture this rotatable member comprises a central body h^2 , provided with a grooved hub h^3 , and an annulus h^4 , which 5 has in one edge a gap h^5 . The body h^2 is provided on one side with a stop-lug h^6 , for coöperation with the stop-lug e' on the relatively fixed member e , and is also provided with a radial slot h^7 , in which is mounted a 10 centrifugal body i , that is, a body which is subject to the action of centrifugal force. This body is provided on one side with a plate i' , formed with a tapered end i^2 to enter and fit the correspondingly shaped gap 15 h^5 in the ring h^4 , so as to fill the same and make a continuous bearing surface on the side face of the rotating member at high speeds; the centrifugal body i is formed with a neck i^3 to enter and travel freely in 20 the slot h^7 and with a keeper i^4 to retain the centrifugal body in place. It will be understood that the centrifugal body is applied to the main body h^2 of the rotating member before the ring h^4 is applied, such ring, 25 which is held in place by screws h^8 , retaining the centrifugal body in operative relation with the central body h^2 . A light spring i^5 , which may be seated upon an adjusting screw i^6 , accessible through an opening i^7 in the ring h^4 , acts to press the centrifugal body i normally inward, against the 30 action of centrifugal force, so that when the speed of rotation falls below the predetermined minimum the centrifugal body moves inward, opening the gap h^5 so that it may be entered by the detector finger e^4 . 35 A spring k , reacting against a fixed ring k' on the shaft c , presses the rotating member h normally toward the relatively fixed member e , this action of the spring being resisted by a bell-crank lever l forked at one 40 end to engage the grooved hub h^3 and connected at the other end, through a spring l' and link l^2 , with the usual controlling treadle 45 so that the operator, by the pressure of the foot on the treadle, may withdraw the rotatable member h from engagement with the fixed member e . The release of pressure on the treadle, as is usual in the operation of 50 high speed sewing machines, effects the disconnection of the sewing machine from the power shaft, through the usual transmission, not shown. At any speed above the predetermined minimum, as already explained, 55 the centrifugal body i , overcoming the action of the spring i^5 , causes the gap h^5 in the ring h^4 to be filled by the outer portion i^2 of the centrifugal body, so that a continuous annular bearing is provided for the end 60 of the detector finger or pin e^4 . As soon, however, as the speed of the sewing machine, after disconnection from the power shaft, falls below the predetermined minimum, the 65 centrifugal body i is moved back by the spring i^5 so as to open the gap h^5 , and as

soon as such gap is presented to the pin e^4 the rotating member h is moved by the spring k toward the relatively fixed member e and the stop-lug h^6 therein, being then in the same plane with the relatively fixed stop-lug e^8 , comes in contact therewith and the motion of the machine is immediately arrested, the shock being cushioned, as hereinbefore explained, by the yielding of the 70 relatively fixed member e . 75

It will be understood that various changes in details of construction and arrangement may be made to suit different conditions of use without departing from the spirit of the invention, which is not limited to the 80 precise construction shown.

I claim as my invention:

1. In a stopping mechanism, the combination of a relatively fixed member, a rotating member, said members being adapted for 85 engagement with each other to stop the rotating member and one of said members being movable toward and from the other, means to press said movable member toward the other, means interposed between 90 said members to prevent the movement of one toward the other, and a centrifugal body carried by the rotating member and adapted to prevent or permit effective operation of said means. 95

2. In a stopping mechanism, the combination of a relatively fixed member, a rotating member, said members being adapted for engagement with each other to stop the rotating member and one of said members 100 being movable toward and from the other, a pin carried by one of said members and adapted to have a bearing against the other of said members to prevent movement of one toward the other, and a centrifugal body carried by the rotating member and adapted to prevent or permit the effective 105 operation of said pin.

3. In a stopping mechanism, the combination of a relatively fixed member, a rotating member, said members being adapted for engagement with each other to stop the rotating member and one of said members being movable toward and from the other, a pin interposed between said members and having a bearing against one of said members to prevent movement of one toward the other, and a centrifugal body carried by the rotating member, said centrifugal body, at 110 speeds above the predetermined minimum, 115 forming a bearing for said pin to prevent movement of one member toward the other and at speeds below the predetermined minimum withdrawing to form a space to receive such pin and permit movement of one 120 member toward the other. 125

4. In a stopping mechanism, the combination of a relatively fixed member, a rotating member, said members being adapted for engagement with each other to stop the 130

- rotating member and one of said members being movable toward and from the other, means to press said movable member toward the other, a detector pin carried by the relatively fixed member, and a centrifugal body carried by the rotating member, said rotating member and centrifugal body forming, at all speeds above the predetermined minimum, a continuous bearing for the detector pin to prevent engagement of the two members, the inward movement of the centrifugal body, at a speed at or below the predetermined minimum, forming in said bearing a gap to receive the detector pin and permit engagement of the two members.
5. In a stopping mechanism, the combination of a relatively fixed member, a rotating member, said members being adapted for engagement with each other to stop the 10 rotating member and one of said members being movable toward and from the other, means to press said movable member toward the other, a detector pin carried by the relatively fixed member, said rotating member being formed with a radial slot and forming on one side face a circular bearing
- track for said pin with a gap therein, and a centrifugal body mounted in said radial slot and adapted, at speeds above the predetermined minimum, to fill said gap and 15 form a continuous bearing track for said pin and at speeds below the predetermined minimum to withdraw and leave said gap open to receive said pin.
6. In a stopping mechanism, the combination of a relatively fixed member, a rotating member, said members being adapted for engagement with each other to stop the 20 rotating member and one of said members being movable toward and from the other, means to press said movable member toward the other, and radially movable, unyielding means carried by one of said members and acting normally to prevent the movement of one toward the other and 25 actuated by a reduction in centrifugal force developed by the rotation of the rotating member to permit the movement of the movable member toward the other.

This specification signed this 21st day of 50 September, 1915.

GEORGE E. MOLYNEUX.
